DESIGN FOR A BABY CARRIER

Lillian C. Lloyd, Woodside, N. Y.

Application September 25, 1943, Serial No. 111,208

Term of patent 3½ years

(Cl. D15—8)

To all whom it may concern:

Be it known that I, Lillian C. Lloyd, a citizen of the United States, residing at Woodside, in the county of Queens and State of New York, have invented a new, original, and ornamental Design for a Baby Carrier, of which the following is a specification, reference being had to the drawing, forming a part hereof.

In the drawing:

Fig. 1 is a front elevational view of a baby carrier, showing my design.

Fig. 2 is a side elevational view.

Fig. 3 is a rear elevational view.

Fig. 4 is a top plan view.

Fig. 5 is a bottom plan view thereof.

I claim:

The ornamental design for a baby carrier, substantially as shown.

LILLIAN C. LLOYD.
